(57) **CLAIM**

The ornamental design for a men's underwear, as shown and described.

DESCRIPTION

FIG. 1 is a top perspective view of a men's underwear, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The dot-dash broken lines in the figures depict a boundary of the men's underwear that form no part of the claimed design. The broken lines outside of the boundary depict portions of the men's underwear that form no part of the claimed design. The remaining broken lines depict stitching, and do form part of the claimed design.
